UNITED STATES PATENT OFFICE.

WALDEMAR DYRSSEN, OF NEW YORK, N. Y.

ELECTRODE PROTECTOR.

Application filed November 15, 1921. Serial No. 515,357.

To all whom it may concern:

Be it known that I, WALDEMAR DYRSSEN, a citizen of the United States, residing in the city, county, and State of New York, have invented certain new and useful Improvements in Electrode Protectors, of which the following is a specification.

This invention relates to means for preventing sectional electrodes from burning away at the joint due to the oxidizing action of the air and the excessive heating in this zone and the increased resistance at the joints.

It is customary in electric furnace practice to feed the electrode down through the roof, and as it burns away in melting the charge to add new sections to the top of the electrode to replace the portions burned off inside the furnace.

I have observed that the current produces an excess amount of heat in the zone of the joint and that the electrode gradually burns away in this location and becomes of considerably less diameter than the other portions thereof. This is due partly to the increased resistance at the joint and partly to the oxidizing effect of the atmosphere at this point.

I have also observed that after the electrode enters the furnace it is not so rapidly burned away at the joint because the atmosphere in the furnace is non-oxidizing. It is very desirable to prevent the reduction of diameter of the electrode before it enters the furnace, it being clear that if the diameter thereof is materially reduced, an enlarged avenue of escape is established for gases of the furnace which results in the loss of heat and otherwise interferes materially with the operation of the furnace.

One object of my invention is to prevent the burning away of the electrode at the joint. Another object is to produce means for protecting the electrode from the destructive action of the atmosphere in the zone of the joint. Another object is to provide a sleeve adapted to readily be applied to the electrode at the time a new section is joined thereto. A further object is to construct a protecting sleeve of a plurality of sections which can be readily lengthened or shortened in accordance with the position of the joint of the electrode with respect to the roof of the furnace.

Other objects will be apparent from the following description when read in connec-

tion with the accompanying drawings in which

Fig. 1 is a diagrammatic view showing the position of the electrode in eleven different stages of operation;

Fig. 2 is an enlarged view in front elevation showing part of the roof of the furnace and my improved protecting sleeve mounted thereon;

Fig. 3 is a horizontal section on the line 3—3 of Fig. 2;

Fig. 4 is a view of a modified form of the device;

Fig. 5 is a horizontal section thereof.

In the drawings the electrode E comprises an upper section e and a lower section e', the sections being joined to each other by a screw threaded plug P. The roof R of the furnace is provided with a suitable opening O through which the electrode passes and the usual cooling ring C in which a circulation of water is maintained as is well understood in this art. Fitting the upper face of the cooling ring is an elongated sleeve S comprising two semi-circular sections s which are detachably secured to each other by means of bolts B provided with thumb nuts N, the bolts B passing through suitable flanges f formed on the sleeve. The sleeve is also provided with a plurality of stiffening ribs s' which also assist in radiating the heat from the sleeve to the surrounding atmosphere. Resting on top of the sleeve S is an upper sleeve S' formed of semi-circular sections and secured together by means of bolts B' and nuts N' similar to the lower sleeve. The lower sleeve is provided with a base flange s² which rests on top of the cooling ring and a peripheral flange s³ which engages the side walls of said cooling ring.

The internal diameter of the sleeves S and S' is slightly greater than the outside diameter of the electrode E so as to permit the latter to be freely moved up and down relatively thereto. Instead of having the inner surface of the sleeves S and S' immediately adjacent to the surface of the electrode, I may space this inner wall a greater distance away, as shown in Fig. 4, so as to provide a chamber s⁴, in the rings, S² and S³. In this form of device I form the sleeves with upper and lower annular flanges s⁵ having apertures s⁶ therein which just clear the outer surface of the electrode E.

The utility of the device will be apparent

from examination of Fig. 1 which diagrammatically shows an electrode in eleven successive positions corresponding to eleven heats of the furnace. These positions are indicated by numerals 1 to 11 for convenience in description.

In the first position the lower end *e'* of the electrode is shown in full lines in the position it occupies after the charge is melted down. The lower end of the electrode is shown in dotted lines, near the surface of the hearth *H* of the furnace, and indicates the position of the electrode when initially melting down the scrap. The electrode is held by means of a suitable holder *G* clamped in the usual manner to an upper portion thereof. It will be apparent from position 1, Fig. 1, that in order to proceed with the operation in the furnace, the electrode must necessarily be lengthened and this is done by inserting the plug *P* in the lower section of the electrode and securing an upper section *e* thereto, as shown in position 2. After this is done my improved sleeves are placed on the cooling ring *C* so as to protect the joint between the two sections of the electrode as it is fed down during the melting operation. This will bring the line of division *D* between the two electrodes within the sleeve, as shown in positions 3, 4, 5, 6 and 7, Fig. 1. When this line of division is located within the sleeves, as shown, the joint is not subjected to the oxidizing effect of free atmospheric air, because the gases escaping between the wall of the sleeve and the surface of the electrode prevent the entrance of air and, therefore, the electrodes do not burn away in this zone as they formerly did before the provision of my improved protecting device.

When the line of division *D*, between the two sections of the electrode approaches the upper surface of the roof of the furnace, it is no longer necessary to have a sleeve of such length and at such time I remove the upper sleeve *S'* using only the lower sleeve *S*, as shown in position 8 of Fig. 1. The lower sleeve *S* is left in place for a few more heats, as indicated at positions 9 and 10, until the line of division is well below the top surface of the roof of the furnace, at which time the sleeves may be entirely removed and the electrode fed downwardly in the usual manner until it again becomes necessary to add a new section to the electrode, as indicated in position 2.

The device is of simple construction and comparatively inexpensive to manufacture and can be applied to existing furnaces without making alterations thereon. It effects an economy in the operation of said furnaces by cutting down the amount of

heat wasted and by preventing destruction of overhead structures by the escape of hot gases around the burned away portions of unprotected electrode joints as heretofore used.

While I have described with great particularity of detail the embodiments of the invention herein shown, it is not to be construed that I am limited thereto, as various modifications and substitution of equivalents may be made without departing from the invention as defined in the following claims.

What I claim is:

1. In an electric furnace the combination of a sectional electrode and a sleeve surrounding the joint thereof and adapted to prevent the electrode from being reduced in diameter by burning away in the zone of the joint.

2. The combination with the roof of an electric furnace and a sleeve comprising a plurality of separable sections above the roof of the furnace surrounding the joint of said electrode and adapted to protect the joint from the oxidizing effect of the atmosphere outside the furnace.

3. The combination with the roof of an electric furnace and a sectional electrode passing therethrough, of a protecting sleeve above the roof surrounding the electrode and arranged to cover the joint of said electrode so as to prevent the electrode from being burned away and reduced in diameter in the zone of the joint.

4. The combination with the roof of an electric furnace, the cooling ring secured thereto and an electrode comprising at least two sections joined to one another, of a protecting sleeve carried by said cooling ring and supported above the roof and adapted to surround and protect the joint at different elevations.

5. The combination with the roof of an electric furnace, the cooling ring secured thereto and an electrode comprising at least two sections joined to one another, of a protecting sleeve formed of a pair of semi-circular sections detachably secured to each other, surrounding said electrode above the roof and adapted to protect the joint thereof from the oxidizing effect of atmosphere at different elevations.

6. In an electric furnace a sectional sleeve for protecting the joint of sectional electrodes, comprising separate sections for varying the length of the sleeve, each of said sections including a plurality of members detachably secured to each other to facilitate their erection and removal.

In witness whereof, I have hereunto signed my name.

WALDEMAR DYRSSEN.
